UNITED STATES PATENT OFFICE.

BARNETT McDougall, of San Francisco, California.

ROOF, CEILING, AND FLOOR CONSTRUCTION.

SPECIFICATION forming part of Letters Patent No. 707,250, dated August 19, 1902.

Application filed February 19, 1902. Serial No. 94,810. (No model.)

To all whom it may concern:

Be it known that I, BARNETT McDougall, a citizen of the United States, residing in the city and county of San Francisco, State of California, have invented an Improvement in Roof, Ceiling, and Floor Construction; and I hereby declare the following to be a full, clear, and exact description of the same.

My invention relates to improvements in the construction of floors, ceilings, roofs, and the like. Its primary object is to provide a horizontal partition which shall have a minimum depth, which shall be as light as is consistent with necessary strength, and which shall depend solely upon the building-walls for support, obviating the necessity of supporting-columns, cross-walls, long arches, or low-hanging trusses, thereby affording greatly-increased floor-space.

It consists, essentially, of a series of joists or beams radiating from a common center, having their outer ends suitably anchored, and concentric bands or rings by which said joists are tied into a rigid structure.

It also includes details and various modifications of construction, which will be more fully set forth hereinafter, having reference to the accompanying drawings, in which—

Figure 1 is a plan view of the structure.

Fig. 2 is a vertical section of the same. Fig. 3 is a similar view showing the use of the truss-rods. Fig. 4 is a view of a corner of the above structure. Fig. 5 is a plan view of a floor, showing truss-rods. Fig. 6 is a similar view showing the use of metallic rings and short truss-rods. Fig. 7 shows the truss-rods fastened to the sides of joists. Fig. 8 is a vertical section of Fig. 5. Fig. 9 is a similar section of Fig. 6. Fig. 10 shows a section through a roof structure.

A represents the supporting-walls of any building or room which it is intended to floor or roof over. The space to be covered may be circular, square, or of other polygonal shape.

In carrying out my invention as shown in Fig. 1, for instance, I take a series of built-up joists 2 and dispose them in such manner that each joist element radiates from a common center 3. These joists or ribs may be constructed of wood, iron, or other suitable material. Each of these joists is composed of

a number of superposed bars, beams, or strips placed either flat or on edge and between which the elements forming the bands or rings 4 are inserted—that is, the joist and band elements are alternately placed in relation to each other, so that when the parts are bound together by nails, spikes, or screws the interlocked parts are united into a rigid skeleton structure capable of sustaining many times its own weight. The outer ends of the joists extend into or through the walls A, which latter simply serve to sustain the weight of the radial floor or roof structure. The bands 4 may be circular, polygonal, or of any other suitable shape. Where they are thus built up and in polygonal form, as in Figs. 1 and 5, they are so disposed one in relation to its successor that they will break joint and form overlapping systems of continuous transverse supports. By this means the weight of each joist and of the load carried thereon is distributed over practically the whole of the floor area, and the entire weight is borne by the walls A. Steel or iron rings 4^a may be used, as in Figs. 3, 6, and 7, consisting of rods or of segmental bars overlapped and united after the manner described in the first instance. This structure may be further reinforced by means of truss-rods 5, which extend diametrically across and beneath the flooring and have their outer ends supported against plates 6 on the ends of the joists. There might be four, eight, sixteen or more of these rods, and by having their ends threaded and provided with nuts 7 their tension may be regulated as desired.

The construction thus described furnishes a skeleton structure excellently adapted for floor and ceiling or for a flat roof. It affords a shallow transverse horizontal partition upon whose upper surface the flooring or roofing may be laid and whose under surface serves as the ceiling of the room beneath. It allows the entire floor-space inclosed by the support-walls to be utilized, doing away with supporting-columns, cross-walls, long arches, or low-hanging trusses.

For an inclined roof the pitch may be varied at will by setting the joists (rafters) at any desired angle and using stout steel rings at either end of the rafters to resist thrust. Intermediate of the ends of the rafters would

be disposed concentric bands or rods of suitable shape, as before.

At times it may be desirable or necessary to provide for a dome-space, skylights, and 5 the like, in which event I form my structure with a central opening 8, as shown in Figs. 1, 3, 5, 7, and 10. In this case the joists or rafters 2^a extend radially, though instead of meeting in the center they abut against and 10 are secured to the steel curbing 9. The joists are tied together by concentric bands or rings and may be reinforced by means of the short truss-rods 5^a, having one end fastened to the curbing 9 and the other end to the sides of 15 the joists, as at 10, or they may be secured to plates 6 on the outer ends of the joists, as shown in Figs. 4 and 5.

Having thus described my invention, what I claim, and desire to secure by Letters Patent, is—

1. A floor and roof construction consisting of a series of joists or bars radiating from a common center, said bars or joists unsupported except at their outer ends, and concentric bands or rings engaging said bars or 25 joists and uniting them into a rigid structure.

2. A floor and roof construction consisting of a series of joists or bars radiating from a common center, said bars or joists supported only at their outer ends, concentric polygonal bands secured to said bars or joists and uniting them into a rigid structure.

3. A floor and roof structure consisting of a series of joists or bars radiating from a common center, and a plurality of concentric, polygonal bands secured to and uniting said joists or bars, said bands lying in break-joint courses.

4. A floor and roof structure consisting of 40 a series of joists or bars radially disposed in

relation to a common center, the contiguous ends of said joists inclosing a central opening, a curbing of steel or like suitable material against which the said contiguous ends abut, and a plurality of concentric binding 45 rings or bands.

5. A floor and roof structure consisting of a series of joists or bars radially disposed in relation to a common center, each of said joists comprising a plurality of superposed 50 strips or plates lying in the same vertical plane, concentric bands or rings alternately disposed between said strip and means whereby the rings and strips are rigidly united.

6. A floor and roof structure consisting of 55 a series of joists radially disposed in relation to a common center, each of said joists composed of a plurality of superposed, inter-spaced strips or plates, concentric bands or rings in the spaces between said strips, and 60 said strips and interlocking bands or rings rigidly secured together.

7. A floor and roof construction consisting of a series of joists or bars radially disposed in relation to a common center, said joists or 65 bars supported only at their outer ends and composed of a plurality of superposed, inter-spaced strips or elements, bands or rings having superposed elements in the spaces between said strips, means by which said joist 70 and ring elements are firmly secured together, and reinforcing radial truss-rods substantially as described.

In witness whereof I have hereunto set my hand.

BARNETT McDougall.
